E. SAMPSON.

Attaching Hubs to Axles.

No 10,552.

Patented Feb 21, 1854.

UNITED STATES PATENT OFFICE.

ELNATHAN SAMPSON, OF CLAREMONT, NEW HAMPSHIRE.

ATTACHING HUBS TO AXLES.

Specification of Letters Patent No. 10,552, dated February 21, 1854.

To all whom it may concern:

Be it known that I, ELNATHAN SAMPSON, of Claremont, in the county of Sullivan and State of New Hampshire, have invented a new and Improved Mode of Attaching Hubs to Axles; and I do hereby declare the following to be a full and exact description thereof, reference being had to the accompanying drawings, making a part of this specification, Figure 1 being a longitudinal section taken through the center of hub and axle, and Fig. 2 a side view of a hub and portion of an axle.

Similar letters refer to corresponding parts in both figures.

I secure the hub A, to the axle B, in the following manner; viz: I first secure to the inner end of the hub, by means of screws or bolts—the band D, which has an inwardly projecting, and smoothly turned ledge E; which ledge, embraces a tube F, and confines it to the hub by means of an outwardly projecting flanch a, on the end of the said tube, which passes between the said ledge E, and the inner end of the hub, as shown in Fig. 1. I place upon the axle, a tube G, which has an outwardly projecting flanch c, and then place the hub upon its journal—the tube F, passing within the tube G, and causing the ledge E, of the cap D, to be em-

braced between the flanches a and c, of the outer and inner tubes F, and G; then by drilling holes through both of the said tubes and into the axle, and inserting a screw f, within the same, the hub will be securely fastened to the axle.

To prevent the entrance of dust within the hub, the inner tube F, is fitted snugly to the axle journal, the tubes are fitted closely one within the other, and a recess is formed in the outer end of the band D, for the flanch c, of the outer tube G, to fit into. The cap C, is firmly secured to the outer end of the hub, in any well known or usual manner.

Having thus fully described my improved manner of confining a hub to its axle journal, what I claim as my invention and desire to secure by Letters Patent, is—

The united band D, and tube F, secured to the inner end of the hub, combined with the tube G, and the axle, by means of the single screw f, in such a manner as to securely confine the hub to the axle, and also exclude the dust from, and retain the oil within the hub, substantially as herein set forth.

ELNATHAN SAMPSON.
